UNITED STATES PATENT OFFICE.

JOHN C. SCHELTER, OF ROCHESTER, NEW YORK.

LAST.

Application filed October 28, 1924. Serial No. 746,423.

To all whom it may concern:

Be it known that I, JOHN C. SCHELTER, a citizen of the United States, and resident of Rochester, in the county of Monroe and 5 State of New York, have invented certain new and useful Improvements in Lasts, of which the following is a specification.

The present invention relates to lasts and more particularly to the type in which the heel part and the fore part are connected together for relative movement. An object of this invention is to provide a construction in which a convex cylindrical bearing surface is provided on one of the parts and 15 a concave cylindrical bearing surface is provided on the other part, the two parts being connected together by a link or bonding member pivoted to both parts and the pivots of the bonding member being so positioned 20 with reference to the center of the cylindrical bearing surfaces that such center, when the last is collapsed, lies below the line through the centers of the two pivots, and, when the last is expanded, lies above 25 the line through the centers of the two pivots a resilient member being interposed between the bearing surfaces and acting as a friction producing device as well as a take up device. Another object of the 30 invention is to provide a last having two parts connected together by a bonding member and having cooperating bearing surfaces with a resilient friction producing device interposed between them. A still further 35 object of the invention is to provide a last having its two parts connected by a rigid bonding member with a resilient take-up device between said last parts.

To these and other ends, the invention 40 consists of certain parts and combinations of parts, all of which will be hereinafter described, the novel features being pointed out in the appended claims.

In the drawings:

Fig. 1 is a fragmentary sectional view 45 of one embodiment of the improved last in an expanded condition;

Fig. 2 is a horizontal section through the 50 improved last as shown in Fig. 1;

Fig. 3 is a view in side elevation of the 55 same embodiment in collapsed condition;

Fig. 4 is a view similar to Fig. 1 of another embodiment of the invention;

Fig. 5 is a view of the inner end of the 55 fore part illustrated in Fig. 1; and

Fig. 6 is a perspective view of the resilient

member arranged between the two lasts for producing frictional engagement between them and for taking up wear.

Referring to the embodiment of the invention illustrated in Fig. 1, 1 indicates the fore part and 2 the heel part. These parts, in this instance, have cooperating bearing surfaces which permit the parts to move relatively to each other for the expansion and collapsing of the last. In this instance, the heel part has a convex cylindrical bearing surface 3 formed at its front portion, the center of this bearing surface being situated at X on the fore part, and 60 the fore part has a convex bearing surface 4, the center of which is also at X on the fore part. To hold the parts during their relative movement, a bonding member 5 is employed preferably in the form of a rigid 65 tubular link which in Figs. 1 to 3 and 5 is pivoted at 6 in the heel part and at 7 in the fore part, the link extending into the opposed ends of the last parts and such 70 last parts being cut to permit a relative 75 movement between the link 5 and the part in which the link is mounted. When the last is in an expanded condition, as shown in Fig. 1, the pivotal point X lies above a line y—y drawn through the centers of the 80 pivots 6 and 7, whereas when the last is in a collapsed condition, as shown in Fig. 3, the pivotal point X lies below the line y—y 85 drawn through the centers of the pivots 6 and 7. As a consequence, when the last is 90 expanded, there is a tendency to draw the two surfaces 3 and 4 together and when the last is collapsed, there is a tendency to separate such surfaces. In order that this binding of the surfaces 3 and 4 on the expansion of the last will not become loose due 95 to the wear after the last has been used for an extended period, a combined take-up device and friction producing device is interposed between the cooperating surfaces 100 and to this end the surface 4 is notched or cut away to provide a seat 8, and, in this seat, the resilient device is arranged. This 105 resilient device, in this instance, is in the form of a concavo-convex resilient plate 9, the radius of which is shorter than the radius of the surface 3 so that the central portion of this plate lies in spaced relation to its seat, while the edges of the plate engage the seat and the plate is held against 110 movement by the sides 10 of the seat. In order that this plate may not interfere with

the movements of the last part, it has a slot or opening 11 through which the bonding member 5 extends, this opening being of sufficient size to permit the bonding member to swing on the fore part.

It is apparent that with this embodiment, when the last is swung from collapsed condition to an expanded condition, the surface 3 will be moved toward the center X and will place the resilient device or plate 9 under tension thereby producing friction in the surface 3, at the same time, the pivots 6 and 7 will be carried above the center X, and this tension on the plate tends to hold the last in an expanded condition.

In the embodiment of the invention shown in Fig. 4, the parts are the same except that the center X' of the cooperating surfaces 3^a and 4^a of the last parts is concentric with the center of the pivot 7. As a consequence, the bonding member 5^a may be secured by two pins 6^a and 6^b in the heel part 2 and will swing only relatively to the fore part. With this arrangement the yielding plate 9^a will be maintained constantly under tension and will hold the last parts yieldingly in any position to which they may be relatively shifted.

In both embodiments, the last parts swing on surfaces formed directly upon said parts, there being employed between the parts a yielding element which tends to take up any wear between the parts and, at the same time, acts to yieldingly hold the last in an expanded condition. In both embodiments a resilient device is employed which resists movement between the last parts and which has an opening through which a bonding member extends. One embodiment of the invention makes it possible to obtain cylindrical bearing surfaces of large area between last parts which are connected together by a bonding member pivoted to both parts, the center of the cylindrical bearing surfaces on the two last parts being so positioned that, when the last is collapsed, this center will lie below a line intersecting both pivots and when the last is expanded, this center will lie above such line so that in expanded condition the bonding member tends to hold the last against collapsing. A resilient curved plate seated on one of the cylindrical bearing surfaces cooperates with another bearing surface to support the bonding member in holding the last expanded, and at the same time produces friction between the last parts and takes up for all wear.

What I claim as my invention and desire to secure by Letters Patent is:

1. A last comprising a fore part having its rear end cut to form a convex cylindrical bearing, a heel part having its forward portion formed with a concave cylindrical bearing cooperating with the cy-

lindrical bearing on the fore part, a bonding member pivoted to the heel part and the fore part, the center of the cylindrical bearings on the heel part and the fore part lying above a line intersecting the centers of the pivots of the bonding members when the last is expanded and below said line when the last is collapsed, one of said cylindrical bearing surfaces having a seat therein, and a resilient member arranged in said seat to cooperate with the other cylindrical surface.

2. A last comprising a fore part having its rear end cut to form a convex cylindrical bearing, a heel part having its forward portion formed with a concave cylindrical bearing cooperating with the cylindrical bearing on the fore part, a bonding member pivoted to the heel part and the fore part, the center of the cylindrical bearings on the heel part and the fore part lying above a line intersecting the centers of the pivots of the bonding members when the last is expanded and below said line when the last is collapsed, the fore part having a seat therein, and a concavo-convex resilient plate arranged on said seat and having an opening through which the bonding member extends, the curvature of the plate being different from that of the cylindrical bearing surfaces.

3. A last comprising a fore part and a heel part having cooperating bearings permitting the relative swinging of the parts, a rigid bonding member connected to both parts and permitting the swinging of the parts on said bearings, and a resilient member arranged between the bearings of the fore part and the heel part.

4. A last comprising a fore part and a heel part having cooperating bearings permitting the relative swinging of the parts, a rigid bonding member connected to both parts and permitting the swinging of the parts on said bearings, and a resilient member arranged between the bearings of the fore part and the heel part, said resilient member having an opening through which the bonding member extends.

5. A last comprising a fore part and a heel part having cooperating bearing surfaces formed thereon to permit the swinging of the parts relatively to each other, a rigid link having a fixed pivotal connection both to the fore part and to the heel part, and friction producing means interposed between the bearing surfaces of the two parts.

6. A last comprising a fore part and a heel part, cooperating bearing surfaces on the fore part and the heel part, a bonding member connecting said parts to permit them to turn on said surfaces, and a resilient member interposed between the surfaces.

7. A last comprising a fore part and a heel part, cooperating bearing surfaces on the fore part and the heel part, a bonding member connecting said parts to permit them to turn on said surfaces, and a resilient member interposed between the surfaces, said resilient member having an opening through which the bonding member turns.

8. A last comprising a fore part, a heel part, a link pivotally connected to the fore part and also to the heel part, and pivoting connection between the fore part and the heel part having a resilient member formed with an opening through which the link extends.

JOHN C. SCHELTER.
